UNITED STATES PATENT OFFICE

2,656,579

RETAINING DEVICE FOR SLIDE FASTENERS

David E. Wilson, Arlington, Va.

Application January 8, 1952, Serial No. 265,373

2 Claims. (Cl. 24—205.11)

1

This invention pertains to retaining devices for slide fasteners, and relates more particularly to a device for preventing the movement of a slider after it has performed the function of fully closing the conventional interlocking slide fastener structure, in the placket of dresses, flies in men's trousers, and other openings in garments where interlocking fasteners are used. There are numerous forms of slider locking devices proposed and in use, some of which are comparatively simple in design and very efficient as long as they remain new. The greater portion of slider locking devices are carried on the slider member or engage locking means at the top of the conventional interlocking slide fastener structure and are subject to constant wear from daily usage and often causes trouble due to difficulty of operation. This means that the wearer of a garment having the slide fastener is confronted with a situation in which he can no longer depend on the satisfactory working of the device and is compelled to go to the expense of replacing the old damaged slide fastener with a new one.

It is therefore an object of this invention to provide a simple constructed retaining device for slide fasteners designed to hold the slide fastener in its fully closed position, usually at the top of the placket or garment opening, at the same time permitting the intentional movement of the slide fastener along the slide fastening structure when it is desired to open or close the garment opening.

It is a further object of the invention to provide a retaining device for sliders that may be permanently attached to the conventional pull-tab of a slide fastener and that may be used to pull the slider open and closed, and that may be attached to the waist band of a garment to provide a positive holding means and prevent unintentional movement of the slide fastener from the closed position on a garment.

It is a further object of my invention to provide a retaining device for slider fastening devices that can be manufactured cheaply by a simple stamping process with a minimum of bending to form a complete single element, having the combined function of holding the ends of the fastener device together and retaining the slider in closed position.

It is a further object of my invention to provide a slider retaining device that can be permanently attached to the conventional form of slide fastener and perform the equivalent in service as provided by the self-locking more costly type of slide fasteners, and also convenient to readily transfer from one garment to another should occasion require.

Another object of the invention is to provide a retaining device for slide fasteners that can be cheaply stamped out and made substantially in one working process of suitable material such as stainless steel, aluminum alloy, nonferrous met-

2

als or plastic material, which is durable and well adapted to withstand the rough usage to which it may be subjected in every day use on a garment.

With these and other difficulties in mind it is an object of my invention to produce a retaining device for slide fasteners which is easy to apply to the pull-tab of a conventional interlocking slide fastener structure, and which when applied will positively remain in permanent engagement at all times with said pull-tab, also to provide means for securing said retaining device to the waist band of a garment, and securely holding the slide fastening device in top most position of its travel on the slide fastener structure thereby providing positive means against movement of the sliding device.

With these and other objects in view the invention will now be described with reference to the accompanying drawings and will be pointed out in the appended claims. In the accompanying drawings, I have shown one embodiment and two modifications thereof which my invention may assume in practice. In the accompanying drawing.

Fig. 1 is a perspective view of the retaining device for slide fasteners as applied to the fly of a pair of trousers, showing the position of the device on a waist band and its manner of engaging the pull-tab when the slider is in full closed position.

Fig. 2 is a similar view showing the retaining device attached to the slide fastener and removed from the waist band of the trousers which are in partly open position.

Fig. 3 is a perspective view of the retaining device for a slide fastener showing the front and rear wing members and the attaching hook for engaging the pull-tab on the slide fastener.

Fig. 4 is a plan view in blank form, showing dotted lines "A" and "B," indicating the bending areas to form the complete single device.

Fig. 5 is a sectional view taken on line V—V of Fig. 1.

Fig. 6 is a sectional view taken on line VI—VI of Fig. 1.

Fig. 7 is a perspective view of a modified form of the retaining device showing an elongated opening in the front wing, to facilitate use of the device where snap fasteners are used to close the garment band.

Fig. 8 is a perspective view of a modified form of the retaining device using plastic as a medium to form the body of the device, showing metal hook attached to plastic body.

Fig. 9 is a sectional view taken on line VIV—VIV of Fig. 8, showing the manner of attaching the metal hook to the plastic front wing of the device.

In the accompanying drawing I have shown for purposes of illustration one embodiment and

two modifications thereof which my invention may assume in practice. In the preferred form I have shown the invention attached to the fly of a pair of trousers as shown in Figs. 1 and 2, although the device is equally adaptable for use in the plackets of dresses, openings in corsets or girdles or other forms of wearing apparel.

Referring more particularly to the drawings, in which similar reference characters identify similar parts in the several views, I have shown in Figs. 1 and 2 a fragmental view of a pair of trousers consisting of waist band 10 attached to a garment in the usual manner, a fly 12 to which is stitched a conventional interlocking slide fastener structure 14. The retaining device for the slide fastener which I shall designate as a whole, as 16, comprises a front wing 18 and a back wing 20 and an integral neck portion 22 forming the body of the retaining device. The integral neck member 22 by virtue of its resiliency when engaged with the waist band 10, causes the front wing member 18 and the back wing member 20 to tightly clamp on the waist band in a manner to securely hold the retaining device in position on the waist band. The front wing 18 is cut away at 24 to form a downwardly extending arm 26 which at its lower end is reduced as shown at 27 on the drawing and terminates into a hook shaped member 28. The hooked shaped member 28 being integral with the reduced portion of said downwardly extending arm, is provided with a depression 30 midway its length, said depression forming a raised stop member 32 on the inside face of the hook shaped member to serve as a means for preventing the unintentional disengagement of the pull-tab 34 carried by the conventional interlocking slide fastener structure. In the cut away portion of the front wing 24 I provide a recessed pocket 38 which is designed to permit the retaining device to slip in back of the fastening button 40 sufficient distance to maintain a vertical alignment of the arm member 26 and its integral hook member 28, with the slider member 36 when in closed position at the top of the fastener structure.

The back wing member 20 is extended downward half of the overall length of the retaining device and terminates in a slightly rounded form. Said back wing member in combination with said front wing member providing a suitable receiving slot 19 when pushed down over the waist band 10 of the garment. The back wing 20 is made shorter than the front wing 18 to facilitate its riding over the waist band 10 when pressed into position on the garment. The retaining device with the pull-tab attached is drawn to the full closed position, and slipped over the waist band, and by reason of its shorter length, the retaining device will have but a short distance to travel downward to seat on the waist band, thus supporting the slider fastener from sagging after reaching the closed position on the garment.

In Fig. 4 of the drawing I have shown a plan view in blank form, indicating by dotted lines "A"—"A" and "B"—"B" the bending areas for forming the device from the blank form. This simple operation of bending and the operation of pressing the stop member 32, is all that is required to complete the device for use as a retaining device for slide fasteners.

In Fig. 7 of the drawing I have shown a modified form of construction in which the front wing member 18 is cut out to form an enlarged oblong

aperture 42 of sufficient proportion to permit the front wing to fit around a pair of snap fasteners 44 when same are used as fastening means on the upper part of a garment. Said enlarged aperture 42 is also adapted to fit around the conventional button 40 which is often placed on the waist band in various positions, not always in direct line with the slide fastener structure. Having this latitude of adjustment is important as it permits the hook member 26 to maintain an alignment with the vertical travel of the pull-tab when same is at the top of the slide fastener structure.

In Fig. 8 of the drawing I have shown another modified form of construction in which the device is formed of thermoplastic with the aperture 46 shown in oval shape in the front wing 18, to fit around the fastening button 40. The hook 30 is of metal and is provided with an extending member 48 which extends through the lower portion of the front wing member and is bent downward at 50 to form a fastening means against displacement as shown in Fig. 9 of the drawing.

It may be noted that I have made reference to the "front wing" and "rear wing" and "neck" of the retaining device for slide fastener and have used the expressions as a convenient way of designating the relative location of the various parts, it will be obvious that the terms are used in reference to the position of the parts as disclosed in the accompanying drawings and are not intended as limiting expressions. It should be further understood that any suitable material may be used in the manufacturing of the retaining device for slide fasteners, and that any variations in the shape and relative arrangement of the parts such as come within the scope of the claims appended herewith are to be regarded as forming part of my invention.

I claim:

1. A retaining device comprising a front wing and a back wing spaced apart by an integral portion to form a hook member, the front wing having its lower portion cut away on one side inwardly from said side edge to provide a recessed pocket and a downwardly extending arm member having a narrow end bent upwardly to form a hook member, said last named hook member being provided with a depression midway its length to form together with the arm member, a constricted passage to prevent displacement of a pull-tab, said back wing member extending downward less than the length of said front wing member to form a receiving slot in combination with said front wing member to receive a garment waist band.

2. The subject matter as claimed in claim 1, said integral hook member being centrally located in relation to the width of said front wing member to form a vertical alignment with a pull-tab attached to a slide fastener.

DAVID E. WILSON.
